The ornamental design for a support leg, as shown and described.

DESCRIPTION

FIG. 1 is a perspective view of a support leg, showing our new design with the broken-line showing of an associated partition panel segment and casters being for illustrative purposes only and forming no part of the claimed design; FIG. 2 is a top plan view; FIG. 3 is a front elevational view; FIG. 4 is a rear elevational view; FIG. 5 is a right side elevational view, the left side being a mirror image; and, FIG. 6 is a bottom plan view.
